[21] Appl. No.: 772,545

[57] CLAIM

[22] Filed: Sep. 4, 1985

The ornamental design for a frame component for a
patio door as shown and described.

[30] Foreign Application Priority Data

DESCRIPTION

Mar. 6, 1985 [GB] United Kingdom 1025408

FIG. 1 is a perspective view of a frame component for
a patio door embodying our design wherein the centre
portion is broken away to indicate indeterminate length;
FIG. 2 is an end elevation view thereof.
